UNITED STATES PATENT OFFICE.

GREENLEAF WHITTIER PICKARD, OF AMESBURY, MASSACHUSETTS.

RADIO TELEGRAPHY AND TELEPHONY RECEIVER.

1,144,969.

Specification of Letters Patent. Patented June 29, 1915.

Application filed April 17, 1914. Serial No. 332,592.

To all whom it may concern:

Be it known that I, GREENLEAF WHITTIER PICKARD, a citizen of the United States of America, and a resident of the town of Amesbury, State of Massachusetts, have invented certain new and useful Improvements in Radio Telegraphy and Telephony Receivers, the principles of which are set forth in the following specification and accompanying drawings, which disclose the form of the invention which I now consider to be the best of the various forms in which the principles of the invention may be embodied.

This invention relates to a system or method of receiving intelligence communicated by electromagnetic waves, the object being a more efficient system of this kind, the invention consisting of the apparatus and methods herein disclosed.

Of the drawings, Figures 1 and 2 are explanatory diagrams; Figs. 3-7 inclusive are diagrammatic illustrations of several of the various useful embodiments of the invention.

The description will be in terms of receipt of continuous or undamped waves with which the invention is most efficient.

A simple embodiment is shown in Fig. 3 wherein the natural period of the antenna-ground connection A, L¹, G, the natural period of the closed resonant circuit C¹ L², and the coupling of these two circuits (variable as indicated by the double arrows) are such, that two oscillating currents of frequencies, which differ from each other, are set up in this system when the same is affected by transmitted electromagnetic waves which are not materially damped. These two frequencies act together to form beats, which have a lower order of frequency as a, b, c, in Fig. 1, the energy periodically rising and falling as indicated. Thus if the oscillating current frequency in one of the above-specified circuits of Fig. 3 is of the order of several tens of thousands per second, and if the frequency of the other is of a like order but slightly lower, then the beat-frequency may correspond with that of audible sounds. This beat-frequency, even when caused to be such as to correspond with sound frequencies within the limits of audibility, will not of itself produce audible sounds in the electromagnetic telephone receivers T (Fig. 3) for the reason that each

beat comprises a group of oscillations of the much higher frequency *i. e.* of the order of several tens of thousands per second, which is far beyond the limits of audibility, and which would not properly operate such a direct current instrument as such telephones. In order to convert the energy of these beats into sound waves of audible frequency, *i. e.* first, in order to cause it to assume such form as will effectively operate the telephones, the beat oscillations are rectified (Fig. 3) by the connection of the rectifier D to the coil L¹ (that is, to that part of this coil which extends to the right beyond the connection to it of antenna A). This rectifying device D may be of any suitable kind, such for example, as the well-known types of crystal rectifier or gas rectifier heretofore used in this art, as detectors. The resulting rectified pulses which operate the telephones T are indicated in Fig. 2 at a¹, b¹, c¹. Thus we have, first, the original frequency of the undamped electromagnetic waves as N transmitted through the ether and received at a given receiving station; second, we have at that receiving station an arrangement of circuits such as those shown in Fig. 3 at A, L¹, G, and at L², C¹, whereby said original frequency is converted into two slightly different frequencies (say N¹ and N²) which produce beats indicated in Fig. 1; and third, we have a means, such as rectifier D (Fig. 3) whereby the beat oscillations are rectified so as to obtain the energy in most efficient form to operate the telephones T and produce an audible communication which has a pitch corresponding with the frequency of the beats.

To explain the invention in greater detail, assume that the two principal circuits of Fig. 3 (*i. e.* the antenna-ground circuit and the closed resonant circuit L², C¹) each has the same natural period N due to its capacity, inductance and resistance, this period being the same as that of the transmitted waves; and assuming further that the coupling of these two circuits has a coefficient K. It is well known that in such a system two oscillating currents will be set up of frequencies differing from each other, frequency N¹ being equal to N divided by the square root of K plus one, and frequency N² being equal to N divided by the square root of one minus K. According to my observation, these two frequencies N¹ and N²

2

and N^2 approach to the common period N in proportion as the coupling of the two circuits in the system is made loose and the period of the resulting beats is so low as 5 to be below the lower limit of audibility. But reversely, as the coupling is made tighter, these two frequencies more widely differ, with the result that the produced beats have a higher frequency. In accordance 10 with this invention, a coupling is employed which causes the production of beats which are of not too high frequency or too low frequency to be outside the limits of audibility. When the coupling is too loose, 15 the current resulting in the telephones from the rectified oscillations of the beats of low frequency corresponding to such loose coupling, will be a smooth, continuous current which fails to operate the telephones to produce 20 an audible sound. Under this condition a tightening of the adjustable coupling between the coils L^1 and L^2 (Fig. 3) results in an increase of the beat-frequency so that when the proper adjustment of coupling is 25 obtained, the formal continuous current in the telephone windings will begin to pulsate; and as the beat-frequency rises above the lower limit of audibility, the telephones 30 T , receiving the rectified current from instrument D , will emit notes corresponding to the frequency of the beats.

This method is efficient for working with undamped waves produced by the well-known transmitters of such waves, such as 35 those including an arc, or an alternator of the frequency of the order of tens of thousands. The method can also be used, however, with spark transmitters, particularly those having slight damping.

40 Fig. 4 differs from Fig. 3 in having an inductive relation of the circuit $D-T$ with the coil L^1 by way of the coil L^2 , and in having this circuit grounded, as shown, at G . In any case where such an inductive relation 45 is employed, the coupling between coils L^1 and L^2 may be varied or adjusted, if desired. In Fig. 5 also the relation of circuit $D-T$ is inductive to coil L^1 by way of coil L^2 , but circuit $D-T$ is not mounted as 50 in Fig. 4, and is provided with a battery-potentiometer circuit $B-P$. In Fig. 6 the coil L^1 is conductively related to coil L^2 by way of rectifier D and by the circuit of the telephones T , battery B and potentiometer coil P . In all of Figs. 3-6 inclusive, the 55 connection of the circuits $D-T$ and the inductance coil or coils is uni-lateral, this connection being made in Fig. 3 to the right hand end of coil L^1 , i. e. the part extending 60 to the right beyond the connection thereto of antenna A ; in Figs. 4 and 5 this connection is made to one end of coil L^2 , and in Fig. 6 this connection is made between the right hand end of coil L^1 and the left hand 65 end of the open-circuited coil L^2 . In Fig.

7, however, the method is employed in a system involving a closed circuit co-operating with the antenna coil L^1 in the open circuit A , L^1 , G , which is preferably adjusted to the periods of the transmitted waves. 70 Here circuit C^1 , L^2 itself is adjusted to the same frequency, but has a variable coupling with coil L^1 . If this coupling is of the proper degree of tightness, as above explained, the beat-frequency set up will be sufficiently high to be within the limits of audibility. The coil L^3 , here as in the other figures, is a pick-up coil for the beat-pulses, and this coil passes said pulses on to the rectifier D which converts the oscillations 75 composing each beat into the proper form to operate telephones T . In this case, however, the circuit of the pick-up coil is not open and is closed through condenser C^2 and this circuit may, if desired, have the same natural period as those of the circuits of the coils L^1 and L^2 , obtained as by adjustment of coil L^3 or condenser C^2 , or both. Here this circuit L^3 , C^2 is shunted by the rectifier-telephone circuit $D-T$ wherein the 80 telephones are shunted by the condenser C^3 . 85

In Figs. 4, 5, and 6, the coil L^3 corresponds with the pick-up coil L^3 of Fig. 7, and in Fig. 3 the coil so corresponding is the right hand part of coil L^1 which extends 90 beyond the connection of antenna A .

As indicated above, the general system and method of this invention is more efficient in proportion as the transmitted waves are substantially undamped, being 100 most efficient with the continued or undamped waves which are emitted from a transmitter employing an arc or an alternator of the high frequency hereinbefore specified. However, the method is also useful in receiving waves which are radiated from transmitters including a spark gap provided that such waves are not too highly damped. 105

I claim:

1. In a system of communicating intelligence by electromagnetic waves which are not materially damped, the combination, at a receiving station, with means for causing such waves of a given frequency to set up oscillating currents of two frequencies differing from each other to such extent as to produce beats of audible frequency, of means for causing the energy of said beats to produce a sound of a pitch corresponding to the frequency of the beats. 110

2. In a system of communicating intelligence by electromagnetic waves which are not materially damped, the combination, at a receiving station, with means for causing such waves of a given frequency to set up oscillating currents of two frequencies differing from each other to such extent as to produce beats of audible frequency, of means for rectifying the oscillations 115 composing said beats, and a telephonic device 120

130

operable by the rectified beat-pulses to produce a sound having a pitch corresponding to the beat-frequency.

3. In a system of communicating intelligence by electromagnetic waves which are not materially damped, the combination, at a receiving station, with two resonant circuits having such periods and coupling as to cause such waves of a given frequency to 10 set up oscillating currents of two frequencies differing from each other to such extent as to produce beats of audible frequency; of a pick-up coil arranged to receive said beat-pulses; means for rectifying 15 the oscillations composing said beats; and a telephonic device operable by the rectified beat-pulses to produce a sound having a pitch corresponding to the beat-frequency.
4. In a system of communicating intelligence by electromagnetic waves which are not materially damped, the combination, at a receiving station, with two resonant circuits having such periods and coupling as to cause such waves of a given frequency to 20 set up oscillating currents of two frequen-

cies differing from each other to such extent as to produce beats of audible frequency; of a pick-up coil arranged to receive said beat-pulses; of means for causing the energy of said beats to produce a sound having 30 a pitch corresponding to the frequency of the beats.

5. In a system of communicating intelligence by electromagnetic waves which are not materially damped, the combination, at 35 a receiving station, with means for causing such waves of a given frequency to set up oscillating currents of two frequencies differing from each other to such extent as to produce beats of audible frequency, of a 40 pick-up coil arranged to receive said beat-pulses; and means unilaterally connected to said pick-up coil, and operable by the energy of said beat-pulses, to produce a sound 45 having a pitch corresponding with the frequency of the beats.

GREENLEAF WHITTIER PICKARD.
